UNITED STATES PATENT OFFICE.

CHARLES H. RHODES AND HARTLEY R. RHODES, OF COLD BROOK, NEW YORK; SAID CHARLES H. RHODES ASSIGNOR OF ONE-HALF OF THE ENTIRE RIGHT TO JOHN F. FISHER, OF COLD BROOK, NEW YORK.

FOLDING CHAIR.

1,178,264.

Specification of Letters Patent.

Patented Apr. 4, 1916.

Application filed February 18, 1915. Serial No. 8,987.

To all whom it may concern:

Be it known that we, CHARLES H. RHODES and HARTLEY R. RHODES, of Cold Brook, in the county of Herkimer and State of New York, have invented certain new and useful Improvements in Folding Chairs; and we do hereby declare that the following is a full, clear, and exact description thereof, which will enable others skilled 5 in the art to which it appertains to make and use the same, reference being had to the accompanying drawings, and to the reference-numerals marked thereon, which form part of this specification.

10 The purpose of our present invention is to provide a folding chair of improved construction and of great strength and rigidity.

A further object is to procure such coöperation of the parts of the chair as to render 15 it well able to stand the strain of use and in fact to make it stiffer and more rigid when in use.

Figure 1 is a side elevation of a chair embodying our invention, part of one leg being 20 broken away to more clearly show the construction. Fig. 2 is a rear elevation of the chair shown in Fig. 1. Fig. 3 is a sectional view on line 3—3 of Fig. 1. Fig. 4 is an enlarged detail of Fig. 1. Fig. 5 is a side elevation of the chair when folded.

Referring to the drawings in a more detailed description the chair has two oppositely disposed pairs of legs, the legs of each pair being pivotally connected to each 25 other at 7, and the upper front ends 8 of the legs of the oppositely disposed pair being rigidly connected by a front cross bar 9 to which is secured in any desired manner the front end of the flexible seat 10.

30 The chair back, formed as a rigid member has sides 11 and cross slats 12. The sides 11 passing downwardly within the extended upper rear ends 13 of the legs, are pivotally connected thereto at points 14 above the level of the seat 10 and extend a short distance below the level of said seat where said sides 11 are rigidly connected 35 by the rear cross bar 15. This rear cross bar 15 extends forwardly for part of its

40 thickness between the upper rear ends 13 of the legs so that the forward part 16 of the ends of said rear cross bar are in close or wedging engagement with the inner surface of the upper rear ends 13 of the legs

when the chair is set up for use. To the 55 rear of the faces 16 the cross bar 15 extends outwardly back of the upper rear ends 13 of the legs forming a projection 17 which when the chair is set up for use acts as a stop to hold the chair upright by coming 60 into engagement with the rear edge of the upper rear ends 13 of the legs. When the chair is set up the engagement of the projecting stops 17 with the rear upper ends 65 13 of the legs prevents the chair opening any farther than is planned and the close or wedging fit between the faces 16 of the cross bar 15 and the adjacent upper rear legs 13 gives great stiffness or rigidity to the entire chair.

70 It will be understood that in folding chairs the pivotally connected parts must be relatively loosely jointed in order to allow the chair to be easily and quickly folded or unfolded. This necessary looseness of 75 pivoting points, however, prevents the chair having the desired amount of rigidity when it is set up and in use. The wedging action above described braces the legs against the rear cross bar 15 and forces the upper rear 80 ends 13 of the legs outwardly and places their pivotal connection at 14 with the sides 11 of the back under tension thereby greatly stiffening the chair when set up and reducing to a minimum any sidewise motion of 85 the chair upon the legs or any twisting action in the chair. As this wedging action against the upper ends 13 of the legs is taken directly as an end thrust upon the faces 16 of the cross bar great stiffness is 90 obtained at this point. Likewise at the pivoting connection 14 the outward strain upon the upper rear ends 13 of the legs communicated through the bolts or rivets at 14 to the sides 11 of the chair back is exerted 95 against the relatively unyielding portion of the sides 11 because these sides are immediately below this point rigidly connected to the rear cross bar 15.

100 Preferably the rear portion of the cross bar 15 is cut away adjacent to its ends to form a shoulder 18 against which the inner side of the lower end of the sides 11 fit while the forward part of this lower end of the sides 11 is cut away to form a 105 shoulder 19 resting down upon the upper side of the cross bar 15 and leaving the rearward part of this end of the side 11 to bear

forward against the rear side of the cross bar 15. We further prefer to make the cross bar 15 in two parts extending longitudinally of the bar and clamped together as by bolts 5 20 so as to hold between the two parts of the bar the rear end of the flexible seat 10. Preferably also the opposing faces of the two parts of this rear cross bar are respectively grooved and tongued as clearly 10 shown in Figs. 3 and 4 to obtain a more secure hold upon the seat material.

A round 21 connects the legs near their lower rear ends, but no round connects the lower front ends of the legs.

15 To fold the chair the crossed legs are brought toward each other at the top and passed slightly by each other and the top of the back folded forwardly until the parts assume the position clearly indicated in 20 Fig. 5.

What we claim as new and desire to secure by Letters Patent is:

The combination in a folding chair of two pairs of crossed and pivotally connected 25 legs, a flexible seat, a cross bar rigidly con-

necting the upper front ends of the legs and supporting the front end of the seat, a back having its sides pivoted to the upper rear ends of the legs on the inner faces thereof above the level of the seat and extending below the seat, and a rear cross bar rigidly connecting the lower ends of the sides of the back and supporting the rear end of the seat, said rear cross bar extending for part of its thickness forwardly between 35 the upper rear ends of the legs and into wedging engagement therewith, when the chair is set up, and having its rearward part extending back of the upper rear ends of the legs and into engagement therewith to 40 form stops holding the chair upright.

In witness whereof we have affixed our signatures, in the presence of two witnesses, this 29th day of Jan. 1915.

CHARLES H. RHODES.
HARTLEY R. RHODES.
